UNITED STATES PATENT OFFICE.

EDWARD E. RICHARDSON, OF TOLEDO, OHIO, ASSIGNEE, BY DIRECT AND MESNE ASSIGNMENTS, TO THE R. & S. VALVE COMPANY, OF ELYRIA, OHIO, A CORPORATION OF OHIO.

RADIATOR SHUTTER.

Application filed January 10, 1920. Serial No. 256,898.

To all whom it may concern:

Be it known that I, EDWARD E. RICHARDSON, a citizen of the United States, and a resident of Toledo, county of Lucas, and State of Ohio, have invented a certain new and useful Improvement in Radiator Shutters; and I do hereby declare the following to be a full, clear, and exact description of the invention, such as will enable others skilled in the art to which it appertains to make and use the same.

This invention relates to air-controlling arrangements for radiators on automobiles and similar apparatus. Shutter arrangements have previously been used on automobile radiators for controlling the flow of air through the radiator, whereby the desired temperature of the cooling fluid may be controlled, but, as far as I am aware, the shutter arrangement for controlling the air has been of such construction that it is hard to operate, and therefore, thermostatic control of the shutters has been more or less unsatisfactory.

One object of my invention is, therefore, to provide a shutter arrangement that will have minimum friction of movement, so that it can be operated by the usual thermostat devices on the market.

Another object is to provide both automatic and manual control.

A further object is to connect indicator devices to the shutter arrangement, so that the driver will at all times know what the position of the shutters is by glancing at a suitable place on the dash or instrument board.

Further objects will be found in the appended description, reference being had to the drawings, in which:

Fig. 1 is an elevation of a radiator and other parts of an automobile with my radiator shutter attached.

Fig. 2 is a front view of the radiator with attached shutters.

Fig. 3 is a section taken on the line A—A of Fig. 2.

Fig. 4 is a sectional plan taken on the line B—B of Fig. 5.

Fig. 5 is a sectional elevation taken on the line C—C of Fig. 4.

Fig. 6 is an elevation of the indicator.

Referring to the drawings, my improvement consists, broadly speaking, in having

a plurality of shutters arranged—in closed position—to contact in such a way as to produce a zig-zag closure, as will be clear from an inspection of Fig. 3. The construction is such that adjacent shutters are rotated in opposite directions, so that maximum opening will be obtained for given movements of the shutter control.

The shutters 1 are pivoted in standards or bearing members 2 secured to projections 3 and 4 on the end shells 5 and 6 at each side of the radiator 7. The journals or shafts 8 of the shutters are secured to pinion members 9, which mesh with a rack member 10 sliding through openings in the projections 3 and 4. The rack member 10 has a central slot and adjacent sides of this are provided with gear teeth 11, 12, which mesh with alternate pinion members, as will be evident from an inspection of Fig. 3.

At the top of rack member 10 is attached a lever 13 which may be pivoted at 14 at the rear part of the shell 5, or at any other suitable place. The end 15 of this lever is attached to the movable member 16, attached at its other end to any suitable thermostat 17. The particular thermostat used is no part of my invention, and a detailed description of it is unnecessary, inasmuch as thermostatic controls are old and well known in the art.

The rack member 10 may be connected for manual control in various ways, but I have provided a series of gear teeth 20 at one side, which mesh with a pinion 21. This pinion is secured to a shaft 22, which extends to the dash or instrument board 23, and is provided with an indicator 24. Instead of manipulating the pinion 21 by means of the indicator, I prefer to utilize another member, such as tube 25, for the manual control. This tube or pipe is adapted to clutch and unclutch with the pinion 21, so that the manual control may be thrown out of engagement when the automatic or thermostatic control is in working condition. Various positive clutches may be used, but I prefer to form cavities in the pinion, which are adapted to mesh with projections 26 on the end of the tube 25.

The tube 25 passes through a bearing member 27 secured to the radiator shell 5, and the other end passes to the indicator device on the dash or instrument board. This

latter consists of a bushing or ferrule 28 passing through the instrument board, with a flange member 29 attached to the board. The bushing 28 is preferably arranged with a diameter sufficiently large to permit the use of a spring 30 therein, one end of which may bear against a collar 31 secured to the tube 25, and the other end against the member 29. In this way the spring tends to 10 maintain the clutch in operative position.

To the end of the tube 25 is attached a collar 32, to which is attached a handle 33 having a lug 34 adapted to seat in a depression 35 in the elevated portion 36 of the 15 flange or plate 29 when in a certain position, and in a series of depressions 37 when in other positions.

The operation of the improvement as described is as follows: When the engine of 20 the automobile is cold, the thermostat 17 will maintain the series of shutters 1 in closed position, or substantially so, as shown in Fig. 3. As the cooling water heats up, due to the running of the engine, the thermostat 25 will gradually move the rack 10 upward in Fig. 3, and this will move the first shutter 1 in a clockwise direction, the next lower shutter in a counter-clockwise direction, and so on. More and more air will be permitted 30 to pass between the shutters and through the radiator 7 in this way as the engine heats up. The cooling water will, therefore, be maintained at the desired temperature by the thermostatic control of the radiator 35 shutters.

As the rack member 10 moves upward, the pinion 21 and shaft 22 are rotated counter-clockwise and the indicator 24 moves to the left in Fig. 6 to give a visible indication of the position of the shutters. When the indicator hand is in the extreme right-hand position, as in Fig. 6, the shutters are closed and when it is over to the extreme position at the left, the shutters are fully 45 opened. The indicator hand will take a position somewhere between these extreme positions as the shutters are moved by the thermostat device. When the thermostat device is controlling the radiator shutters, the 50 handle 33 of the manual device will be moved so that the lug 34 rests in depression 35, and since this is higher than the lower portion of the plate 29, the tube 25 will be maintained in an outward position, where 55 the lugs 26 of the positive clutch will be free of the pinion. The manual control will, therefore, not hamper the automatic control. When, however, the automatic control gets out of order, the operator can 60 rotate handle 33 around onto the lower portion of plate 29, where in some position the lugs 26 will "pick up" the pinion by clutching into the depressions therein. Movement of the handle 33 then will either open 65 or close the shutters by rotating the pinion

21, and the shutters will be maintained in any desired position by the lug 34, registering with the depressions 37.

It will be noted from the drawing that the spring 30 tends to maintain the tube in 70 clutched position with the pinion 21 and by arranging the projections 26 on the tube, in such a way that there is room for additional movement into the pinion member, the spring will press the lug 34 into the depressions 35 to yieldingly hold the lever in 75 position. Also, the spring will maintain the lever in the other position by yieldingly holding it in depression 35.

In my improvement the indicator 24 gives 80 the position of the radiator shutters, regardless of whether the manual or the automatic control is in operative position.

I have described one particular embodiment of my improvement, but it will be apparent that various modifications may be made without departing from the spirit of the invention.

Having described my invention, what I 90 claim is:

1. In automobiles, a radiator for cooling fluid, bearing members adjacent the sides of the radiator, shutters journaled in said members and adapted to be rotated into engagement to form a zig-zag closure in front of said radiator, a reciprocating member engaging the journals of the said shutters and adapted to rotate simultaneously alternate shutters in one direction and the other shutters in the opposite direction, and means for moving said member.

2. In automobiles, a radiator for cooling fluid, bearing members adjacent the sides of the radiator, shutters journaled in said members and adapted to be rotated into engagement to form a zig-zag closure in front of said radiator, a reciprocating member engaging the journals of the said shutters and adapted to rotate simultaneously alternate shutters in one direction and the other shutters in the opposite direction, means for moving said member, a hand-lever connected to said reciprocating means, and automatic means responsive to temperature of the cooling fluid for moving said reciprocating means.

3. In automobiles, a radiator for cooling fluid, shutters journaled adjacent said radiator, manually-operated means for rotating said shutters, automatic means responsive to the temperature of the cooling fluid for moving said shutters, and a clutch between said manual means and the said shutters to connect and disconnect the same therefrom.

4. In automobiles, a radiator for cooling fluid, shutters journaled adjacent said radiator, an indicator connected to said shutters and adapted to move therewith, and means for rotating said shutters in opposite 800

directions simultaneously to control the quantity of air entering said radiator.

5. In automobiles, a radiator for cooling fluid, shutters journalled adjacent said radiator, an instrument board, an indicator on said board and connected to move with said shutters and means for moving the shutters in opposite directions simultaneously to control the quantity of air entering said radiator.

6. In automobiles, a radiator for cooling fluid, shutters journalled adjacent said radiator, an indicator connected to said shutters and adapted to move therewith, manual means for moving said shutters, automatic means responsive to temperature of the cooling fluid for moving said shutters, and a clutch for connecting and disconnecting said manual means from said shutters.

7. In automobiles, a radiator for cooling fluid, shutters journalled adjacent said radiator, a bar connected with said shutters, a pinion meshing with said bar, an indicator connected with said pinion, automatic means responsive to temperature of cooling

fluid for moving said shutters, manual means for moving said shutters and a clutch for connecting and disconnecting said manual means.

8. In automobiles, a radiator for cooling fluid, shutters journalled adjacent said radiator, a rack bar pivotally connected to the journals of said shutters, a pinion meshing with said bar, an indicator connected to said pinion, automatic means responsive to temperature of the cooling fluid for moving said bar, manual means for moving said pinion, and a clutch for connecting and disconnecting said manual means.

9. In automobiles, a radiator for cooling fluid, a plurality of shutters journalled in bearings adjacent said radiator, and means engaging the journals of said shutters for rotating alternate shutters simultaneously in opposite directions to control the quantity of air entering said radiator.

In witness whereof, I have hereunto signed my name this 6th day of Jany., 1920.

EDWARD E. RICHARDSON.
